UNITED STATES PATENT OFFICE

RAYMOND P. LANSING, OF MONTCLAIR, NEW JERSEY, ASSIGNOR TO ECLIPSE MACHINE COMPANY, OF ELMIRA HEIGHTS, NEW YORK, A CORPORATION OF NEW YORK

ENGINE-STARTING APPARATUS

Application filed October 25, 1928. Serial No. 315,042.

This invention relates to engine starting apparatus, and more particularly to combined starting and ignition mechanism for internal combustion engines.

- 5 One of the objects of the present invention is to provide novel engine starting mechanism including an inertia starter and a booster magneto adapted to be driven by the starter during the starting operation.
- 10 Another object is to provide novel means for drivably connecting a booster magneto with the flywheel of an engine starter whereby ignition current is generated during the starting operation.

- 15 Another object is to provide novel manual means for drivably connecting and disconnecting the starter and booster magneto.

A further object is to provide novel manual means for operatively connecting the booster magneto with the flywheel of an engine starter, the manually operable means being combined with meshing means for a jaw or other clutch member adapted to be driven by the flywheel of the starter and also adapted to be moved into driving engagement with a member of the engine to be started.

A further object is to provide, in combination with an inertia starter and a booster magneto adapted to be driven thereby, novel means for drivably connecting the magneto and starter including a meshing rod for the magneto slidably mounted in the starter cranking shaft.

A still further object is to provide, in combination with an inertia starter of the type having a clutch member movable into engagement with a member of the engine to be started, a booster magneto adapted to be drivably connected to said starter, in combination with novel means for establishing the driving connection between the starter and magneto simultaneously with the movement of the clutch member into driving engagement with the engine to be started. The above and other

45 objects will appear more fully hereafter in the detailed description of the invention.

Two embodiments of the present invention are illustrated in the accompanying drawings wherein like reference characters refer to like parts throughout the several views. It

is to be expressly understood, however, that the drawings are for purposes of illustration only and are not designed as a definition of the limits of the invention, reference being had for this purpose to the appended claims. 55

In the drawings—

Fig. 1 is a top plan view of one embodiment of the present invention, the starter and driving connections to the magneto being illustrated in section;

Fig. 2 is a detail perspective view of a portion of the meshing mechanism shown in Fig. 1;

Fig. 3 is a detail perspective view illustrating the magneto meshing mechanism and driving means shown in Fig. 1;

Fig. 4 is a top plan view of another embodiment of the invention, the starter and the driving connections to the booster magneto being shown in section; and

Fig. 5 is a perspective view of a portion of the meshing mechanism shown in Fig. 4.

Referring to the embodiment of the invention shown in Figs. 1 to 3 inclusive, the starter comprises a housing embodying an inner section 6 that is preferably formed of aluminum, an intermediate section 7 that is removably secured to section 6 as by means of bolts 8, and an outer section 9 that is secured to section 7 in any suitable manner as by means of screws (not shown). The inner section is provided with a flange 10 that is adapted to be bolted or otherwise removably connected to the engine crank case, a portion of the latter being diagrammatically illustrated at 85 11. The intermediate housing section 7 is provided with an end wall or diaphragm 12 having a laterally projecting boss 13 in which are positioned a pair of ball bearings 14 for rotatably supporting a flywheel 15 which is of small size and weight and which is adapted to be rotated at very high speeds, whereby energy may be stored therein for starting the engine. 90

Means are provided for manually rotating flywheel 15. In the form shown said means includes a hollow cranking shaft 16 which is disposed substantially at right angles to the axis of rotation of flywheel 15 and is rotatably mounted in the intermediate 100

housing section 7. The diaphragm 12 is provided with a lug 17 carrying a ball bearing 18 for rotatably supporting the inner end of shaft 16 and the side wall of section 7 carries a ball bearing 19 for rotatably supporting the outer end of said cranking shaft. A spacing sleeve 20 surrounds the intermediate portion of the cranking shaft and bears at its opposite ends against the inner races of bearings 18 and 19 whereby the latter are maintained in proper spaced relation.

The cranking shaft 16 is provided with an enlarged portion 21 which extends laterally from the outer wall of section 7 and carries closely adjacent the end thereof a transverse pin 22 adapted to be engaged by a hand crank (not shown) whereby said shaft 16 may be manually rotated. The inner end of shaft 16 has drivably connected thereto, in any suitable manner, a bevel gear 23 that meshes with a bevel gear 24 which is drivably connected to a stub shaft 25 which is preferably formed integrally and concentrically with the closed end 26 of a barrel 27 that is rotatably mounted as by means of ball bearings 28 in the inner housing section 6.

Three planetary gears, one of which is shown in section at 29, are rotatably mounted on the outer face of the barrel end 26. As shown, the mounting for each planetary gear 30 is constituted by a screw 30 that is disposed parallel to stub shaft 25 and is threaded at its inner end into barrel end 26. Surrounding the shank of the screw is a sleeve 31 having its inner end countersunk in barrel end 26 and interposed between the sleeve and the planetary gear is a ball bearing 32. The planetary gears are spaced at angular intervals of 120° around the end of the barrel and screws 30 carry on their outer ends a ring 33 which constitutes a retainer for each of the sleeves 31 and ball bearings 32.

An internal spur gear 34 which is rigidly attached to the inner surface of housing section 6, as by means of screws or studs 35, surrounds and has meshing engagement with each of the planetary gears 29. The latter also mesh with a sun gear 36 which is rotatably mounted, by means of a bushing 37, on the stub shaft 25. The sun gear is preferably formed integrally with an internal spur gear 38 which is likewise rotatably mounted on the stub shaft 25 and said internal gear meshes with a pinion 39 formed on one end of a bell-shaped member 40, the large end of said bell-shaped member being cut to form a spur gear 41. A pinion 42, which is formed integrally with the inner end of a stub shaft 43, meshes with the spur gear 41. The stub shaft 43 extends through and is drivably connected to the hub 15^a of the flywheel and longitudinal movement of said shaft relative to the flywheel is prevented by means of a flange 43^a provided on the shaft adjacent pinion 42 and a nut 44 that is threaded onto the outer

end of said shaft and is held in position by means of a lock washer 45 that has abutting engagement with the outer face of flywheel 15.

The energy stored in the flywheel is adapted to be imparted to a clutch or jaw member 46 carried by the crank shaft 47, or an extension thereof, of the engine to be started, and for this purpose the flywheel is drivably connected through the train of gearing described above with a clutch or jaw member 48 that is adapted for movement into, but is normally out of engagement with, jaw member 46.

The energy stored in flywheel 15 is so great that damage would result to the starter parts at the time the starter is connected to the engine if said flywheel were rigidly connected to the clutch member 48. Accordingly, a yielding driving connection is provided between the flywheel and the clutch member 48. In the form shown the yielding driving connection is constituted by a clutch of the multiple disk type, said clutch being positioned within the rotatable barrel 27. A number of the clutch disks 49, which are annular in form, are splined at their outer peripheries to the inner surface of barrel 27 for rotation therewith. The remaining disks of the clutch are splined at their inner peripheries to the outer surface of an interiorly threaded nut 50 which is provided intermediate its ends with a flange 51. The clutch disks 49 are held between flange 51 and the inner face of end wall 26.

Yielding means are provided for varying the frictional engagement of the disks whereby the amount of torque transmitted by said disks may be varied. For this purpose the inner surface of the inner end of barrel 27 is threaded to receive an adjustable nut 52 which has engagement with a spacer ring 53 provided with a plurality of equi-spaced pins 54, each of which extends into a coil spring 55. These springs bear at one end against flange 51 and serve to hold the clutch disks 49 in frictional engagement. By adjusting the position of nut 52 relative to barrel 27 the compression of the springs may be varied, thereby varying the pressure exerted by said springs through flange 51 on the clutch disks. Any suitable locking means, such as is shown at 56, may be employed for locking the nut 52 in adjusted position.

A threaded shaft 57 is positioned within the interiorly threaded nut 50, the shaft being adapted for rotary and longitudinal movement relative to said nut. The outer end of shaft 57 carries a stop nut 58 adapted to engage a suitable shoulder formed interiorly of nut 50 whereby longitudinal movement of the shaft is positively limited. The inner end of shaft 57 is provided exteriorly with longitudinal splines which coact with the interiorly splined hub portion 48^a of the jaw 48. A coil spring 59 is interposed be-

tween jaw member 58 and the adjacent end of shaft 57 to resist movement of said jaw towards the shaft and, if desired, the shaft may be provided with a recess to receive the adjacent end of spring 59. Oil-sealing means 60 are preferably provided for the engine end of the starter to prevent seepage of oil from the engine crank case into the starter housing.

Means are provided for moving shaft 57 and jaw 48 toward the jaw member 46 whereby said jaws may be moved into driving engagement and the energy stored in flywheel 15 may be rendered available for rotating crank shaft 47. As will be pointed out more fully hereafter, said means also serve to establish the driving connection between the magneto and flywheel. In the form shown, the starter is provided with a longitudinally and concentrically disposed rod 61 which slidably extends through jaw member 48, threaded shaft 57, the closed end 26 of the barrel, and stub shaft 25, the outer end of said rod terminating closely adjacent the inner face of pinion 42. The inner end of rod 61 is of reduced diameter to provide a shoulder 62 which normally is in abutting engagement with the outer end of threaded shaft 57. The inner extremity of rod 61 is threaded to receive a nut 63 which bears against the inner face of jaw member 48.

The outer end of rod 61 is provided with a transversely extending pin 64 which passes through a slot 65 provided in one end of a lever arm 66, the opposite end of said arm being rigidly connected to a rockshaft 67 journaled in the starter housing. One end of the rockshaft 67 projects through the starter housing and has fixedly attached thereto a bell crank lever 68 adapted to receive a rod or cable (not shown) whereby said rockshaft may be manually rotated. A coil spring 69 surrounds rockshaft 67 and has one end thereof in engagement with lever arm 66, the other end of said spring being anchored in any suitable manner whereby the same normally maintains rod 61 in the position shown in Fig. 1 with jaw 48 in retracted or non-driving position.

A small, light booster magneto 70 is conveniently mounted on the starter housing and means are provided for drivably connecting said magneto and flywheel whereby the latter may drive the magneto at high speed. In the form illustrated, magneto 70 is mounted on the end of housing section 9 in such a position that the magneto armature shaft 71 extends substantially at right angles to the axis of flywheel 15. A pinion 72, which is carried on the outer end of shaft 71 meshes with a bevel gear 73 fixedly secured to one end of a shaft 74 which is rotatably mounted in a housing 75 provided on the side of the starter housing. The inner end of shaft 74 carries a pinion 76 adapted to be

drivably engaged but normally out of engagement with a bevel gear 78 which is slidably mounted on the enlarged end of crank shaft 16.

A slot 79 is provided in shaft 16 and slidably extending therethrough, at substantially right angles to the longitudinal axis of the shaft, is a pin 80 which engages at its opposite ends the hub portion of bevel gear 78, the pin thus constituting a driving connection between shaft 16 and said bevel gear. The bevel gear 78 is normally maintained out of driving engagement with pinion 76 by means of a spring 81 which is preferably of the single helico-volute type and which surrounds the enlarged portion 21 of shaft 16, the outer end of said spring bearing against a collar 82 which surrounds portion 21 and is held in place thereon by pin 22. The inner end of spring 81 bears against a suitable portion of the gear 78.

Means are provided for moving gear 78 outwardly into driving engagement with pinion 76 against the tension of spring 81 and said means are preferably so constituted as to be actuated by lever 68, rockshaft 67 and arm 66. As shown, a rod 83, which may be formed in sections if desired, slidably extends through the hollow cranking shaft 16, the outer end of said rod having abutting engagement with pin 80 and the inner end of the rod being provided with a U-shaped head 84. Diagonally disposed slots 85 are provided in the opposite sides of head 84 and through said slots project the opposite ends of the pin 64 carried by rod 61. One end of each slot 85 is preferably enlarged, as shown in Fig. 3, and normally pin 64 extends through said enlarged portions.

The operation of the apparatus is as follows: The operator engages the hand crank (not shown) with pin 22 and rotates cranking shaft 16. This movement is transmitted, through the train of gearing described, to flywheel 15 whereby the latter may be rotated at high speed and energy stored therein for starting the engine. As soon as the flywheel is brought to the desired speed of rotation the operator actuates lever 68 to rotate rockshaft 67 which motion is transmitted to the arm 66 whereby the latter is moved in a clockwise direction as viewed in Figs. 1 and 2. The movement of arm 66 is transmitted through pin 64 to rod 61 forcing the latter downwardly as viewed in Fig. 1. Threaded shaft 57, which is rotated by the flywheel through the train of gearing, the multiple disc clutch and the nut 50, and which also rotates during the manual cranking operation, is forced downwardly by shoulder 62 whereupon spring 59 is effective to move jaw 48 into driving engagement with jaw 46 and the energy of the flywheel is imparted to crank shaft 47 to rotate the same.

Simultaneously with the movement of rod

61, pin 64 is effective through the slotted head 84 to move rod 83 to the right. Pin 80, which has abutting engagement with the rod 83, is also forced to the right against the tension of spring 81 and bevel gear 78 is thus moved into meshing engagement with pinion 76, whereupon the flywheel is effective to rotate the magneto armature shaft 71. The magneto now supplies starting current to the engine and when the latter starts under its own power the speed of the crank shaft 47 is such as to cause jaw 46 to overrun jaw 48, whereupon the inclination of the teeth of said jaws forces jaw 48 out of driving position. When the operator releases lever 68 spring 69 returns the rods 61 and 83 to normal position and spring 81 is now effective to demesh gear 78 by moving the latter to the left. It will be noted that gear 78 rotates in unison with shaft 16, which is a low speed shaft and hence the meshing of said gear 78 with pinion 76 is readily effected.

Referring to the embodiment of the invention illustrated in Figs. 4 and 5, the 25 starter, per se, there shown is substantially identical to the one shown in Fig. 1. The cranking shaft 86 of this second embodiment, however, is elongated and has secured to the outer end thereof, as by means of a pin 87, a socket member 88 to receive a hand crank (not shown). The inner end of socket member 88 is rotatably mounted in a boss 89 provided in a housing 90 which is secured in any suitable manner to or is formed integral 30 with the housing of the starter. Surrounding shaft 86 and positioned within the inner enlarged end of socket member 88 is a sleeve 91 having the inner end thereof toothed to engage teeth formed on the outer end of the hub portion 92 of a gear 93 which is rotatably mounted in housing 90. A pin 94 which slidably extends through an elongated slot 95 in shaft 86 constitutes a driving connection between said shaft and sleeve 91 but permits 35 sliding movement of the sleeve on the shaft.

Gear 93 meshes with a pinion 96 carried by a stub shaft 97 that is rotatably mounted in housing 90 and preferably said pinion is formed integrally with a gear 98 which is 40 also carried by stub shaft 97, said pinion and gear meshing respectively with a gear 99 and a pinion 100 carried by a stub shaft 101 rotatably mounted in housing 90 and substantially parallel to shaft 97. Gear 99 meshes 45 with a pinion 102 that is drivably connected to a shaft 103 rotatably mounted in housing 90, one end of said shaft 103 projecting from the housing and having rigidly pinned thereto a toothed coupling member 104 which is in driving engagement with a 50 toothed coupling member 105 that is drivably connected in any suitable manner to the tapered end 106 of the armature shaft of the magneto 70.

65 A coil spring 107 is positioned in a pocket

108 provided in the cranking shaft 86, said pocket opening into the slot 95 formed in said shaft. Spring 107 has abutting engagement with pin 94 and tends to move and hold the toothed end of sleeve 91 in driving engagement with the toothed hub portion of gear 93. Normally the tendency of spring 107 is counteracted by spring 69 which acts through rockshaft 67, arm 66, pin 64, head 84 and rod 83 to hold said sleeve out of driving engagement as shown in Fig. 4.

70 After flywheel 15 has been energized by means of the hand crank, engaged with member 88, lever 68 is actuated to move jaw 48 into driving engagement with jaw 46. Simultaneously, pin 64 is effective due to the inclination of the slots in head 84 to move rod 83 to the right as viewed in Fig. 4. Spring 107 now moves sleeve 91 into driving engagement with gear 93 and the energy of the flywheel is transmitted through shaft 86, sleeve 91 and the gearing in housing 90 to the armature shaft 106 of the magneto. When the parts are returned to normal position by means of spring 69, rod 83 and pin 94 act 85 to compress spring 107 and to force sleeve 91 to out of driving engagement with the gear 93.

80 There is thus provided a combined starter and booster magneto particularly adapted for starting internal combustion engines, such, for example, as are employed in aeroplanes. The driving connection between the magneto and the flywheel is established after said flywheel has been brought to a high speed of rotation, the means for establishing 90 said connection being common to the means for drivably connecting the flywheel with the engine crank shaft. The apparatus is compact and of light weight, factors of considerable importance in air craft structures. 95 Since the magneto is driven at high speed the same may be of small size without interfering with its effectiveness to supply the necessary ignition current to the engine.

100 Power means, such as an electric motor, may be employed to actuate the cranking shaft and energize the flywheel if desired.

105 Only two embodiments of the invention have been illustrated and described in detail, but it is to be expressly understood that the invention is not limited thereto since it will now be readily apparent to those skilled in the art that various changes may be made in the details of construction and arrangement of the parts without departing from 110 the invention defined in the following claims.

115 What is claimed is:

1. In an apparatus for starting internal combustion engines, a flywheel, means for rotating said flywheel at high speed including a cranking shaft, the cranking shaft constituting a driven member after the flywheel has been energized, a rotatable member adapted to be driven by said flywheel, and means 120 interposed between the rotatable member 125

and the cranking shaft for transmitting motion of the flywheel to the rotatable member.

2. In combination with an engine starter embodying a flywheel, a manually operable cranking shaft for rotating the flywheel, said cranking shaft becoming a driven member after the flywheel has been energized, a booster magneto having an armature shaft adapted to be driven by the flywheel, and motion transmitting means for operatively connecting said armature shaft and flywheel, one element of said motion transmitting means being constituted by said cranking shaft.

3. In starting mechanism for internal combustion engines, a flywheel, a cranking member for energizing said flywheel, said member constituting a driven member after the flywheel has been energized, means including a rotatable member adapted to be driven by the flywheel, and means drivably connected to the cranking member for actuating said rotatable member.

4. In apparatus of the type embodying a booster magneto mounted on and adapted to be driven by an inertia starter having a flywheel adapted to be energized by means of a cranking shaft, gearing drivably connected to the magneto, a gear member movably mounted on and drivably connected to said cranking shaft, and means for moving said gear member into driving engagement with said gearing whereby the armature shaft of the magneto is rotated.

5. In apparatus for starting internal combustion engines including a booster magneto mounted on, and adapted to be driven by, a starter of the flywheel type, means including a cranking shaft for rotating the flywheel of the starter, gearing operatively connected to said magneto, a member slidably and drivably connected to said cranking shaft, and means for moving said slidable member into and out of driving engagement with said gearing.

6. In apparatus of the type embodying a booster magneto mounted on and adapted to be driven by, an inertia engine starter having a cranking shaft for energizing the flywheel of the starter, gearing drivably connected to the magneto, a member drivably connected to the cranking shaft, said member being adapted for driving engagement with the gearing, and means including a rod slidably in said cranking shaft for controlling the engagement and disengagement of said member with the gearing.

7. In combination with an engine starter including a flywheel and a driven member movable into engagement with a member of the engine to be started, a booster magneto having an armature shaft, means for drivably connecting said flywheel and armature shaft including a slidably mounted rod having a slotted head, and means for moving said driven member into engagement with the member

of the engine to be started, said last named means being adapted to actuate said slidable rod.

8. In combination with an engine starter embodying a flywheel adapted to be actuated by a cranking shaft and also adapted to rotate a member movable into engagement with the crank shaft of the engine to be started, a booster magneto carried by said starter and having an armature shaft, gearing operatively connected to said armature shaft, a member adapted to drivably engage said gearing and slidably mounted on said cranking shaft, means normally maintaining said slidably mounted member out of engagement with said gearing, and means for moving said driving member into engagement with the gearing, said last named means being adapted to move the first named member into driving engagement with the engine crank shaft.

9. In apparatus of the class described wherein the armature shaft of a booster magneto is adapted to be driven by the flywheel of an inertia starter, a slotted cranking shaft adapted to be rotated by said flywheel, a driving member slidably mounted on said cranking shaft, means movable in the slot of said shaft for drivably connecting the slidable member and the cranking shaft, motion transmitting means operatively connected to said armature shaft and adapted to be engaged by said slidable member, and means for moving said slidable member into and out of operative engagement with said motion transmitting means.

10. In combination with an engine starter provided with a flywheel, a member driven by the flywheel and movable into driving engagement with a member of the engine to be started, and a cranking shaft, a booster magneto having an armature shaft carried by said starter, means for actuating said armature shaft including a gear member mounted on and drivably connected to said cranking shaft, means for moving the driven member into engagement with the member of the engine to be started, and means actuated by said last named means for moving said gear member into driving relation with the armature shaft.

11. In combination with an inertia starter including a flywheel, a flywheel cranking shaft and a driven member adapted to be moved into engagement with a member of the engine to be started, a magneto having an armature shaft, means including a member carried on the cranking shaft for transmitting power from the flywheel to the armature shaft, means for moving the driven member into engagement with the member of the engine to be started, and means, including a rod slidably in said cranking shaft, actuated by said second named means for establishing a driving connection to the armature shaft.

- through the member carried on the cranking shaft.
12. In combination with an engine starter of the flywheel type having a cranking shaft for rotating the flywheel, a rotatable member adapted to be driven by the flywheel, a driving member carried by said cranking shaft and adapted for operative driving engagement with the rotatable member, a pin for drivably connecting the driving member with the cranking shaft, the latter being provided with an elongated slot through which said pin slidably extends, manually operable means having engagement with said pin for moving the driving member into driving engagement with said rotatable member, and resilient means for moving said driving member out of engagement with the rotatable member.
13. In combination with an engine starter of the flywheel type, a rotatable member adapted to be driven by said flywheel, motion transmitting means interposed between said flywheel and rotatable member including a cranking shaft and a gear member slidably mounted on said shaft and drivably connected thereto, yielding means for normally maintaining said gear member in non-driving position, and means carried by the cranking shaft for positively moving said gear member into driving position whereby the flywheel is rendered effective to drive said rotatable member.
14. In combination, an engine starter including a flywheel and a cranking shaft for the flywheel, a rotatable member adapted to be driven by the flywheel, gearing operatively connected to the rotatable member, a gear member adapted to drivably engage but normally out of engagement with said gearing, means for drivably connecting said gear member and cranking shaft, and means carried by the cranking shaft for positively moving said gear member into and out of engagement with said gearing.
15. In combination, an engine starter including a flywheel and a cranking shaft for the flywheel, a rotatable member adapted to be driven by the flywheel, motion transmitting means connected to said rotatable member, a driven member slidably on and drivably connected to said cranking shaft, said driven member being adapted for engagement with the motion transmitting means, means for normally maintaining the driven member out of engagement with said motion transmitting means, and means slidable in the cranking shaft for moving the driven member into engagement with the motion transmitting means.
16. In combination with an engine starter provided with a flywheel and having a cranking shaft, a booster magneto having an armature shaft carried by said starter, means for transmitting motion from the cranking shaft to the armature shaft including a member carried by said cranking shaft and a pin for drivably connecting said member and cranking shaft, and means for moving said member into and out of motion transmitting position, said last named means including a coil spring and a rod slidable in the cranking shaft and having abutting engagement with said pin.
17. In combination with engine starting mechanism embodying a flywheel adapted to drive a magneto and a member movable into engagement with a member of the engine to be started, a cranking shaft for the flywheel, gearing for drivably connecting said flywheel and magneto including a gear slidably mounted on said cranking shaft, means including a member slidable in said cranking shaft for controlling the position of said slidably mounted gear, and manually operable means for actuating said first named member and for longitudinally moving the member in the cranking shaft.
- In testimony whereof I have signed this specification.
- RAYMOND P. LANSING.
